United States Patent

Des. 239,920
Patented May 18, 1976

239,920

PACKAGING CONTAINER FOR A RAZOR OR THE LIKE

Carl H. Floren, Whitman, Mass., assignor to
The Gillette Company, Boston, Mass.

Filed May 13, 1974, Ser. No. 469,595

Term of patent 14 years

Int. Cl. D9—03

U.S. Cl. D9—186

Fig. 1

Fig. 2

Fig. 3

FIG. 1 is a perspective view of a packaging container for a razor or the like showing my new design;

FIG. 2 is a top plan view thereof; and

FIG. 3 is an elevational view thereof.

I claim:

The ornamental design for a packaging container for a razor or the like, substantially as shown.
